ABSTRACT OF THE DISCLOSURE

A process for the production of alkylated tars comprising reacting a lower olefin, in the presence of a silica-alumina or zeolite type catalyst, with a tar fraction obtained by the thermal decomposition of a petroleum hydrocarbon at 700–2300° C., and if desired, following a desulfurization reaction.

BACKGROUND OF THE INVENTION

Field of the invention

The present invention relates to a process in which a lower olefin is reacted with a tar fraction consisting essentially of polycyclic aromatic compounds to thereby obtain a product comprising a mixture containing compounds having alkyl side chains.

The process of this invention is also directed to the efficient utilization of tar fractions and finds its significance in the disposal of heavy cracked oil byproducts which are now being produced in ever increasing amounts as the result of enlargement in ethylene manufacturing plants.

Description of the Prior Art

After extensive studies of the properties and utilization of tar fractions obtained by the high temperature cracking of petroleum oil, the present inventors have now found that these tar fractions comprise polycyclic aromatic compounds having extremely few side chains, and that any impurities initially contained in the petroleum oil, such as sulfur, nitrogen, metal, etc. are converted into gas or pitch during thermal cracking thereby leaving a tar fraction having a greatly reduced impurity level. After investigating methods of reacting these tar fractions with olefins, we have accomplished the present invention.

The tar fraction presently employed is obtained from the heavy cracking oil obtained by thermally cracking petroleum hydrocarbons at a temperature above 700° C. and below 2300° C., and subsequently removing solid pitch from the heavy cracked oil, and which consists of a fraction boiling at 200° C.–500° C., calculated at normal pressure.

The structure of these fractions are determined by gas chromatography, infrared absorption analysis, nuclear magnetic resonance analysis, mass spectograph etc. It has been found that the main component structure of the fractions consists mainly of from two to five benzene nuclei, particularly from two to four condensed benzene rings having short side chains, such as methyl groups, attached thereto, i.e., polycyclic aromatic compounds substantially free from side chains.

This structure differs from that of petroleum asphalt, usually called tars, and also from that of coal tar obtained by the dry distillation of coal, by the following points:

Petroleum asphalt consists of a mixture of polycyclic aromatic compounds having a plurality of long alkyl side chains, long chain paraffinic compounds and naphthenic compounds having aromatic or alkyl groups attached

2

thereto; due to the fact that petroleum asphalt does not undergo a heat treatment at a high temperature, as is the case with the present invention.

On the other hand, coal tar is highly aromatic and resembles the tar fraction of this invention, since it undergoes a heat treatment at high temperatures, but it contains greater amounts of impurities, i.e., oxygen, sulfur, nitrogen metals etc., and has more of a heterocyclic structure in the coal than is contained in petroleum oil.

Thus, the tar fraction utilized in the present invention is clearly a special type of tar. The alkylated tar products of this invention are unique and can be obtained only by reacting a lower olefin with the above-described tar fraction.

SUMMARY OF THE INVENTION

The present invention provides a process for producing alkylated tars by reacting a lower olefin with certain tar fractions, in the presence of a silica-alumina or zeolite type catalyst; the tar fractions being polycyclic aromatic compounds produced by the thermal decomposition of petroleum hydrocarbons at a temperature of from 700 to 2300° C.

DETAILED DESCRIPTION OF THE PREFERRED EMBODIMENTS

In the process of this invention, the thermal cracking of the petroleum hydrocarbons may involve flame cracking, high temperature steam cracking, coil cracking, sand cracking etc., that is, any process by which the feed petroleum oil is thermally cracked at a temperature above 700° C. and below 2300° C. to form acetylene and olefins such as ethylene, propylene, butylene, together with heavy cracking oil formed as a byproduct.

The particular petroleum hydrocarbon employed includes any type readily available in industry such as gaseous hydrocarbons, naphtha, light oil, heavy oil, residual oil, mixtures thereof, and crude oil.

The tar fractions to be used are those obtained from the heavy cracking oil after removing solid pitch therefrom, and which have a boiling point of from 200 to 500° C., calculated at normal pressure, preferably from 250° C. to 450° C. This fraction exhibits a hydrogen to carbon atomic ratio (H/C) of from 0.5 to 1.0, and a specific gravity of from 1.0 to 1.3.

The feed olefin is a lower olefin generally having a carbon number of not higher than 8, preferably those having from 2 to 4 carbon atoms. Typical olefins to be used are therefore ethylene, propylene and butylene. The use of these last-mentioned olefins is economically advantageous.

Prior to the reaction of the olefin with the tar fraction it is desirable to desulfurize the tar fractions, if necessary, in order to markedly prolong the catalyst life during the alkylation.

The desulfurization may be conducted in a conventional desulfurizing apparatus and is operated by reacting hydrogen with the tar fraction in the presence of a catalyst to thereby remove sulfuric compounds in the tar fraction as hydrogen sulfide. The catalyst employed in the desulfurization may contain cobalt, molybdenum or nickel in the form of free metal, oxides, sulfides or combinations thereof, supported by a suitable carrier such as silica-alumina. The desulfurizing reaction is carried out at a temperature of 350–450° C., under a pressure of 20–100 kg./cm.² using a feed ratio (molar ratio of hydrogen to the tar fractions) of 3–15 mole/mole and at a liquid hourly space velocity (L.H.S.V.) of 0.5–10 cc./cc.-catalyst/hr. Under such conditions, the desulfurization reaction takes place readily while attaining a good desulfurizing effect.

3

The alkylation reaction is conducted by mixing the gaseous olefin with the tar fraction which has been (or has not been) previously desulfurized, and passing the mixture over a solid catalyst bed under specified reaction conditions. The alkylation apparatus may be a conventional fixed bed type reactor. The reaction conditions will be more fully described below.

The catalyst to be used is preferably a solid acid type catalyst including, for example, silica-alumina, or a group III-B metal of the Periodic Table such as lanthanum (La), cerium (Ce), thorium (Th) etc. supported on a zeolite carrier.

The reaction takes place more rapidly as the temperature is increased, but the inverse reaction and a polycondensation reaction will begin to take place at a temperature exceeding a certain limit, so that there is maximum reaction rate depending upon the temperature. The rate also increases as the pressure is increased from atmospheric to superatmospheric, but a polycondensation reaction takes place at a pressure exceeding a certain limit. Further, the ratio of feed composition influences the degree of alkylation. As the olefin:tar fraction ratio increases, the degree of alkylation becomes larger; i.e., the mole numbers of olefin reacting per mole of tar fraction. Usually, excess olefin is fed to the system and unreacted olefin may be re-used by recycling it. The liquid hourly space velocity (L.H.S.V.) is the liquid volume of flowing tar fraction per unit hours per unit catalyst volume, and the decrease of L.H.S.V. from a higher to a lower value will increase both the reaction conversion and the degree of alkylation but will reduce the product yield.

As a result of the above considerations, it is economically advantageous to set the preferred reaction conditions as follows: a temperature between 250° C. and 380° C., a pressure between 1 and 50 kg./cm.², a feed ratio between 0.2 and 10, and a L.H.S.V. between 0.1 and 50 cc./cc.-catalyst/hr. The degree of alkylation is varied by varying the L.H.S.V. while the length of the alkyl group in the tar fraction is varied by varying the particular olefin fed into the system. Under the above-mentioned reaction conditions, neither the decomposition nor the polycondensation reaction occurs and the loss in material balance is minimal. Moreover, the decrease in catalyst activity due to carbon deposition is greatly minimized so that the catalyst may be used over a prolonged period.

The alkylated tar thus formed has a lower specific gravity and a lower refractive index as well as a higher H/C, viscosity, average molecular weight and boiling point than that of the feed tar fraction. By analysis of the alkylated product utilizing gas chromatography, infrared absorption spectrum, nuclear magnetic resonance etc., the alkylated tar is estimated to have a chemical structure consisting of condensed polycyclic aromatic rings having from two to five, particularly from 2 to 4, benzene rings, which are combined with alkyl groups having the same carbon number as that of the olefin used in the reaction. When ethylene, propylene or butylene is used as the olefin, the resulting alkylated tar has as its main component an ethylated, propylated or butylated polycyclic aromatic compound, respectively.

As described, this invention provides a process for synthetically producing novel alkylated tar fractions having various alkyl group side chains, from polycyclic aromatic compounds substantially free from side chains. Accordingly, various alkylated tars having desirable properties can be produced depending upon their desired uses.

The alkylated tar produced by the process of the present invention is used as an electric insulating oil, a rubber processing oil, a heat transfer oil, a plasticizer and as an intermediate material in organic synthesis, etc. The present invention will be more fully illustrated by reference to the following examples, which are merely illustrative, and not intended to be limiting, in nature.

Example 1.—Petroleum naphtha was thermally cracked

4

according to a flame cracking process at a temperature of 1200° C. for a contact period of 0.003 second to obtain a heavy cracking oil from which a relatively lower boiling tar fraction having a boiling point of 250–350° C. (calculated at normal pressure) was taken for use as a feed stock. The physical properties of this fraction were measured by gas chromatography, infrared absorption analysis, nuclear magnetic resonance, mass spectrograph analysis, etc. in order to determine its chemical structure. The result of the analysis indicated that the tar fraction consisted mainly of aromatic compounds having two or three condensed aromatic rings to which a few methyl side chains were attached, and was substantially free from naphthenic and paraffinic components. The other physical properties are given in Table 1 below.

Ethylene having a commercial grade purity of 99% was used as the olefin feed. The reactor used was a stainless steel tube 1000 mm. in length and 25 mm. in diameter. The catalyst used was granular silica-alumina (SiO₂ 87%, Al₂O₃ 13%). The reaction was started by preheating the tar fraction, without desulfurizing treatment, to 200° C., then mixing it with the ethylene and passing the mixture to the reactor after adjusting the feed molar ratio (ethylene to tar fraction) to 5. The reaction was carried out at a reaction temperature of 300° C., a pressure of 30 kg./cm.², and a liquid hourly space velocity (L.H.S.V.) of 0.25 cc./cc.-catalyst/hour. The reaction conditions and the properties of both the tar fraction and the resulting alkylated tar are shown in Table 1 below. The degree of alkylation, i.e., the mole number of added ethylene per mole of tar fraction, increases, as shown in Table 2, as the feed molar ratio increases, and it also increases as the L.H.S.V. decreases as shown in Table 3. Thus, the degree of alkylation was controlled depending upon the feed molar ratio and the value of L.H.S.V. During the course of the operation, the reaction proceeded with ease without causing a decrease in catalyst activity. Though the ethylated tar so produced had somewhat of a deeper yellow-brown color than the feed tar, it could be converted into clear liquid after distillation or acidic clay treatment. The ethylated tar so obtained exhibited excellent electric insulating properties, i.e., in volume intrinsic resistance, dielectric constant, dielectric tangent, etc., and it was also found to have superior rubber processing properties, that is, as a plasticizer for polyvinyl chloride. Moreover, many organic compounds may be derived from the alkylated tar and hence it is a very useful substance.

Example 2.—Petroleum naphtha was thermally decomposed according to a high temperature steam cracking process at a temperature of 1,500° C. for a contact time of 0.002 second to form a heavy cracking oil from which a relatively high boiling tar fraction, boiling at 350–450° C. (calculated at normal pressure), was collected and used as the feed material. The reaction apparatus and the manner of operation were the same as employed in Example 1, and the reaction conditions and the properties of the product are given in Table 4. From these results, it is noted that the ethylation reaction takes place readily when using a higher boiling tar in place of the lower boiling tar fraction as the feed.

Example 3.—Ceria crude oil was thermally decomposed according to a high temperature steam cracking process at a temperature of 1000° C. for a contact time of 0.005 second to form a heavy cracked oil from which a wide ranged tar fraction, boiling from 250 to 450° C., was collected and used as the feed. This tar had a somewhat higher content of sulfur than the tar fraction obtained from the petroleum naphtha, i.e., the former containing 0.224% by weight, and the latter containing 0.072% by weight, sulfur, so that the former tar fraction was desulfurized to a sulfur content of 0.001% by weight prior to alkylation. The alkylation was then conducted using an alkylation catalyst containing 1.5% by weight of cerium supported on a zeolite carrier. The reactor and operation were the same as in Example 1. The reaction conditions and properties of feed and products are given in Table 5. From these results, it is noted that the alkylation reaction takes place smoothly by using a cerium-zeolite catalyst as well, and the life of the alkylation catalyst is extended by preliminarily desulfurizing the crude tar which contains a relatively large amount of sulfur compounds.

Example 4.—Using the feed tar fraction of Example 1, the alkylation was conducted with propylene. The reactor and operation were the same as in Example 1. The reaction conditions and the properties of feed and product are given in Table 6 (reaction No. (5)). This shows that the process of this invention can be readily performed using propylene as well as ethylene.

Example 5.—The tar fraction used in Example 1 was alkylated with butylene (mixture of butylene-1 and butylene-2). The reaction apparatus and operation were the same as in Example 1, except that a different olefin was employed as the starting material. The reaction conditions and the properties of the material and product are shown in Table 6 (reaction No. (6)). It is obvious from 15 the results obtained that the alkylation of the tar fraction with butylene also proceeds easily.

Example 6.—Petroleum naphtha was thermally cracked at 800° C. for a contact time of 0.5 second to produce ethylene and propylene. A fraction having a boiling point of 250° C. to 350° C. was extracted from the bottom oil occurring as the byproduct during the thermal cracking procedure. The fraction obtained was desulfurized with a cobalt/molybdenum/alumina type catalyst using the same apparatus as used in Example 3, and then propylated with propylene. The results obtained are shown in Table 7, together with the reaction conditions.

What is claimed is:

1. A process for the production of alkylated tar which comprises:
  - (a) cracking petroleum oil in a thermal reaction at a temperature of from 700° C. to 2,300° C. to obtain a fraction having a boiling point at normal pressure of from 200° C. to 500° C., having a hydrogen to carbon atomic ratio of 0.5 to 1.0, having a specific gravity of 1.0 to 1.3 and having chemical structure consisting essentially of polycyclic aromatic compounds substantially free from side chains;
  - (b) desulfurizing said fraction with hydrogen in the presence of a desulfurizing catalyst at a temperature

in the range of 350-450° C. and a pressure of 20-100 kg./cm.²; and

(c) alkylating said desulfurized fraction with a lower olefin of 2 to 4 carbon atoms in the presence of an alkylation catalyst selected from the group consisting of silica-alumina catalyst and zeolite catalyst.

2. A process as in claim 1 wherein said alkylation catalyst comprises a zeolite support having catalytic material comprising a Group III-B metal thereon.

3. A process as in claim 1 wherein said desulfurization is conducted at a feed ratio of moles of hydrogen to moles of tar fraction of from 3 to 15 and at a liquid hourly space velocity of from 0.5 to 10 cc./cc.-catalyst/hour.

4. A process according to claim 1 wherein said alkylation is carried out at a temperature from 250 to 380° C., at a pressure from 1 to 50 kg./cm.², with the liquid hourly space velocity of said tar fraction being from 0.1 to 50

cc./cc.-catalyst/hr., and with the molar ratio of reacted olefin/tar fraction being from 0.15 to 3.45.

5. A process according to claim 1 wherein said fraction has a chemical structure consisting of said polycyclic aromatic compounds.
